UNITED STATES PATENT OFFICE.

JACOB S. SHERMAN, OF CHICAGO, ILLINOIS, ASSIGNOR TO UNIVERSAL LAMP COMPANY, OF CHICAGO, ILLINOIS, A CORPORATION OF ILLINOIS.

DESIGN FOR A SMOKER'S ASH RECEIVER.

Application filed October 21, 1925. Serial No. 15,206. Term of patent 14 years.

To all whom it may concern:

Be it known that I, JACOB S. SHERMAN, a citizen of the United States, residing at Chicago, in the county of Cook and State of Illinois, have invented a new, original, and ornamental Design for Smoker's Ash Receiver, of which the following is a specification, reference being had to the accompanying drawing, forming a part hereof.

In the illustration,

Fig. 1 is an elevational view of an ash receiver showing my new design

Fig. 2 is a top view of the same, and

Fig. 3 is another elevational view of the same.

What I claim is:

The ornamental design for a smoker's ash receiver, substantially as shown.

JACOB S. SHERMAN.
